Henry to Messerrey

Henry to Messerrey, Message for Mr. Sitter:
Delivered January 30, 1866.

DES. 2257

Henry G. Mescury of Boston Mass.

Letter Patent No. 2257 Dated Jan. 30, 1846

Design for a Stone Sifter

The schedule referred to in these Letter Patent and making part of this same.

To all whom it may concern:

Be it known that I, Henry G. Mescury of Boston
in the County of Suffolk and State of Massachusetts, have invented
a new Design for a Stone Sifter, of which, the following is a full,
clear and exact description, reference being had to the accompanying
drawings, making part of this specification, in which

Fig. 1. is a perspective view of my Stone Sifter.

Fig. 2. is an end elevation of the same.

In the said drawings A is the body or hopper of the
sifter, the bottom or screen of which is rounded; one side B, of the hopper
A is nearly vertical and is provided with a handle C, while the oppo-
site side D, is inclined to the vertical as seen in the drawings. The legs
E, are formed of pieces of structure bent in the form shown, and
secured to the ends of the hopper A.

Claim

What I claim as my invention, and desire to secure
Letter Patent is, the Design for a Stone Sifter herein set forth.
